(57) **CLAIM**

I claim the ornamental design for cheesecake martini dessert, as shown.

DESCRIPTION

FIG. 1 is a front-top perspective view of the cheesecake martini dessert. (The back-top perspective view being a mirror image thereof.); and,

FIG. 2 is a top view of the cheesecake martini dessert. (The bottom of the dessert glass is flat and unornamented.)

1 Claim, 2 Drawing Sheets

FIG. I.

FIG. 2.
